UNITED STATES PATENT OFFICE.

EDWARD L. ADAMS, OF BRADFORD, PENNSYLVANIA.

GARMENT RECEPTACLE AND HANGER.

1,228,732.

Specification of Letters Patent. Patented June 5, 1917.

Application filed July 10, 1916. Serial No. 108,409.

To all whom it may concern:

Be it known that I, EDWARD L. ADAMS, a citizen of the United States, residing at Bradford, in the county of McKean and

5 State of Pennsylvania, have invented certain new and useful Improvements in Garment Receptacles and Hangers, of which the following is a specification.

My invention relates to a garment folding 10 retainer as applied to garments when folded in suitable containers for storage or transportation, or with wardrobe trunks and the like, and my improvements are in the nature of devices designed to hold the various parts 15 of a garment in properly folded position to insure their being maintained in wearable condition and free from wrinkles at all times.

It is well understood by those skilled in the art, that garments can be folded in certain ways to preclude the causing of wrinkles, creases and the like, and when properly maintained in such folded position they may be transported or laid away from one season to another, and still be preserved 25 in a wearable condition.

To this end my invention consists of a garment holder for application to, and in combination with a shipping box or container, wardrobe trunks and the like, and the same in its preferred form consists of a suitable hanger shaped to conform to the shoulders of a coat with coöperating holding and retaining devices, which may be secured to opposite sides of the container and adapted 30 to engage the free edge portions of the garment, while other retaining devices engage and hold the sleeves, and other parts of the garment in extended formation, substantially as hereinafter described.

40 With these and other objects in view the invention consists in the novel details of construction and combination of parts more fully hereinafter disclosed, and particularly pointed out in the claims.

45 Referring to the accompanying drawings forming a part of this specification,

Figure 1, is a front elevation of the container showing the hangers and retaining devices, and illustrating in dotted lines the 50 position of a garment therein.

Fig. 2, is a view in vertical section on the lines A—A, shown in Fig. 1, looking in the direction of the arrows.

55 Fig. 3, is a view in vertical section on the lines B—B, shown in Fig. 1, looking in the direction of the arrows.

Fig. 4, is a front elevation of a modified form of the invention, in which a metal frame is used in supporting the garment retaining clamps.

Fig. 5, is an enlarged detail view in perspective of one of the retaining clamps.

Referring to the construction in further detail as exemplified by the drawings, 1 represents the bottom of the container or box 65 which may be constructed of any suitable material such as wood, fiber, cardboard and the like, and it may be made to fold in such compact form as is well known in the art. Attached to the upper wall 2, of the box is a 70 suitable bracket 3, suspending the supporting medium 4, which consists of a curved bar in the form of an ordinary clothes hanger, which is adapted to engage the neck and shoulder portions of a coat. Attached 75 to the ends of the supporting medium 4, are downward projecting bars 5, and 5'. Located below the supporting medium 4, and connected at the opposite ends thereof to the downward projecting bars 5 and 5', is a 80 cross bar 6, forming another garment supporting medium, the functions of which will hereinafter more fully appear. Depending from the cross bar 6, and suitably attached to the downward projecting bars 5 and 5', is 85 an inner casing or compartment 7. This casing is so attached to the downwardly projecting bar 5', by hinges 8 and 8', as to permit of its being swung outwardly thereon, and to be suitably attached in its fixed position to the bar 5, by the fasteners 9 and 9'. The inner casing 7, is further adapted to be 90 used as a receptacle for other articles of clothing, and for that purpose is provided with a door 20, adapted to be opened on the 95 hinges 21 and 21', and to be fastened in a closed position by the latch 22.

When the garment, as a coat is placed within the container, and properly engaged by the hanger 4, it will be evident that the 100 neck and shoulder portions of the coat will be kept in proper position when normally suspended in a vertical position. To maintain the garment in this position, as if suspended from the hanger 4, and to preserve 105 the rounded and smoothly pressed effect of the neck, shoulders and breast portions of the garment, I provide as is shown in Fig. 5, a well known form of spring clamp 10 and 10', as staying devices to be made fast to the 110 lapel edges of the garment. Clamp 10' is attached by suitable tension providing means

to the outer edge of the inner compartment 7, and is adapted to engage the edge of the garment lapel. Clamp 10, is likewise attached by suitable tension providing means to the inner side wall of the container, and is adapted to engage the outer edge of the garment. It being understood that the garment in the folded position designated, encircles the inner casing or compartment 7.

10 To provide for maintaining the front edge portions of the garment in proper position, I provide engaging clamps 11 and 11', attached by suitable tension providing means to a retaining bar 12, placed at the bottom of 15 the container. To further provide for maintaining the lower edge extensions of the garment, I provide clamps 13 and 13', likewise suitably connected with tension providing means to the bar 12. To maintain the garment sleeves in an extended formation, I provide similar clamps 14 and 14', likewise suitably attached through tension providing means with the bar 12. With the various edges of the garment thus yieldingly attached to suitable retaining means, the container may be handled or placed in any position without danger of the garment becoming displaced, wrinkled or affected by such movement. In placing a garment comprising 25 a man's suit within the container, the inner compartment 7, is swung outwardly and the lower extremities of the trousers are passed over the bar 6, and downwardly in a plane between the container wall 1, and the 30 downward projecting bars 5 and 5', until the lower extremities are in a position to be engaged by the clamp 15. In this position the upper portions of the trousers will be suspended downwardly and in a position to be 35 engaged by the back wall of the inner casing 7, as it is swung into position, and made fast by the fasteners 9 and 9'. With this portion of the garment thus held firmly in position, the clamp 15, may be attached to 40 the lower extremities with sufficient tension applied thereto, to maintain this portion of the garment in extended formation.

In the modified form illustrated in Fig. 4, the inner casing 7 is dispensed with, and a 45 supporting frame 16 is substituted therefor. The frame 16 is formed of spring wire or other suitable material having at its outer portion an eye 17, adapted to engage hooks or other supporting means within the container. Suspended from the eye 17, is a suitable bracket or stirrup 3', which supports a 50 suitable hanger or supporting medium 4'. Attached to the supporting medium 4', is a rectangular wire frame 18, to which is attached the clamp 10', adapted to retain the inner edge of the garment in extended formation. To suitably maintain the trousers in extended formation the clamp 19, is attached to the waist band thereof, and is suitably connected through tension providing 55

means with the lower bar of the rectangle 18. From the clamp 19, the trousers are passed upwardly over the upper horizontal bar of the rectangle 18, and in a downward direction and attached to the clamp 15. The lower horizontal bar of the frame 16, serves the purposes of staying the various clamps in the same manner as bar 12, shown in Fig. 1.

In the modification shown and illustrated 75 in Fig. 4, I have provided a simple device for maintaining garments in wearable condition at all times, and which may be adapted to be readily inserted in a fixed wardrobe, a wardrobe trunk and the like, and may be 80 placed in its entirety within any of the common forms of cardboard containers, commonly used for shipping and storing of garments. Another use to which the modification may be put to advantage, is the insertion 85 thereof within the common form of moth proof paper bags with the assurances that the garment will be maintained in a wearable condition therein.

It is obvious that those skilled in the art 90 may vary the details of construction and arrangement of parts without departing from the spirit of my invention, and therefore I do not wish to be limited to such features except as may be required by the claims. 95

Having thus described my invention, what I claim as new and desire to secure by Letters Patent of the United States is as follows:

1. A garment receptacle of the character 100 described, comprising a casing having fixed garment supporting means, and detachable garment edge staying means yieldingly attached to fixed supports, whereby tension is applied between the garment edges and the 105 fixed supports.

2. In a garment receptacle the combination 110 of an outer casing, an inner casing having a garment supporter integral therewith surrounded by said outer casing, with detachable garment edge staying means yieldingly attached to the outer casing, whereby tension is applied between the garment edges and the outer casing.

3. In a garment receptacle the combination 115 of an outer casing, an inner casing surrounded by said outer casing, with means for maintaining a garment folded around the inner casing, by maintaining the garment edges yieldingly extended.

4. In a garment receptacle the combination 120 of an outer casing, an inner casing surrounded by said outer casing, with means for maintaining a garment folded around the inner casing by detachable edge staying 125 means yieldingly attached to the outer casing, whereby tension is applied to the garment edge staying means between the edges and the outer casing.

5. In a garment receptacle the combina- 130

tion of an outer casing, an inner casing having garment supporting means, with means for maintaining a garment folded around said inner casing, comprising detachable 5 garment edge staying means, with means for applying tension to the edge staying means and the inner casing garment supporting means.

6. The combination of a garment receptacle comprising a casing having fixed garment supporting means, and detachable garment edge staying means, with means for applying a tension to the garment edge between the fixed means and the detachable 10 means.

7. The combination of a garment receptacle, comprising a container having a garment hanger secured to the inner wall thereof and supported therefrom, with detachable garment edge staying means yieldingly attached to fixed supports within said container, and adapted to provide tension between the fixed supports and the garment edges, substantially as described. 15

25 8. A garment receptacle comprising an outer case having therein fixed garment supporting means spaced one above the other,

an inner case depending from the upper supporting means, and spaced apart from said outer casing, means for maintaining a garment in folded position over said lower supporting means, means for supporting another garment positioned to surround said inner casing, and detachable staying means adapted to engage the free edge portions of 30 35 said garments.

9. A garment receptacle comprising an outer casing, a supporting member depending from the inner wall of said casing, side members projecting downwardly from the 40 supporting member, an inner casing spaced apart from said outer casing having a hinged connection with the side member, and adapted to swing open, means for supporting the garment positioned to surround 45 said inner casing, and detachable staying means adapted to engage the free edge portion of said garment.

In testimony whereof I have affixed my signature in presence of two witnesses.

EDWARD L. ADAMS.
